UNITED STATES PATENT OFFICE.

DAVID W. HAWKSWORTH, OF DETROIT, MICHIGAN, ASSIGNOR TO HUTCHINS CAR ROOFING COMPANY, OF DETROIT, MICHIGAN, A CORPORATION OF MICHIGAN.

CAR-ROOF.

1,122,498.

Specification of Letters Patent. Patented Dec. 29, 1914.

Application filed August 29, 1910. Serial No. 579,554.

To all whom it may concern:

Be it known that I, DAVID W. HAWKSWORTH, a citizen of the United States of America, residing at Detroit, in the county 5 of Wayne and State of Michigan, have invented certain new and useful Improvements in Car-Roofs, of which the following is a specification, reference being had therein to the accompanying drawings.

10 The invention relates to car roofs of the type in which metallic roofing sheets are employed, said sheets being provided with down-turned flanges at the eaves, and the invention consists in the construction as 15 hereinafter set forth.

In the drawings,—Figure 1 is a cross section through a portion of the car roof; Fig. 2 is a perspective view of the depending flange of the roofing sheet.

20 In the construction of car roofs of the above described type, it is usual to nail the depending flange of the roofing sheet to the fascia of the car. This frequently results in the collection of moisture between the 25 metal and the wood causing the former to rust and the latter to rot. The present invention is designed to overcome this defect by spacing the flange from the outer surface of the fascia so as to provide an air chan- 30 nel for drying any moisture.

As shown, A is the side plate of the car, B is the fascia and C is the roofing plate having a depending flange D.

E is a bolt or other securing device for 35 fastening the flange D to the fascia. The flange D is spaced from the fascia throughout the greater part of its extent and this is preferably accomplished by embossing portions to form inwardly projecting bear- 40 ings F that contact with the fascia. This also forms on the outer face of the sheet a recess G to receive the head H of the bolt.

The sheet constructed as described when secured in position will provide a narrow 45 channel or air space between the inner face

of the metal and the outer face of the wood in all portions excepting the bearings F. These being limited in extent and surround- 50 ed by the air space will have any collecting moisture eliminated.

What I claim as my invention is:

1. In a car roof, the combination with the fascia, of a metallic roofing sheet having a depending flange overlapping said fascia, said flange being inwardly embossed to form 55 a bearing against the fascia, said bearing spacing the body of the flange from contact with the fascia and forming a vertically open air space.

2. In a car roof, the combination with 60 the fascia, of a metallic roofing plate having a depending flange overlapping said fascia, said flange being inwardly embossed to form a bearing lug separating the body 65 of the flange from the fascia to form a vertically open air space, and a securing bolt passing through said inwardly embossed portion.

3. In a car roof, the combination with 70 the car side, of a metallic roofing sheet hav- 75 ing a depending flange adjacent to said side, said flange being provided with means for holding the greater portion of said flange out of contact with said car side.

4. In a car roof, the combination with 80 the car side, of a metallic roofing sheet hav- 85 ing a depending flange adjacent to said side, said flange being provided with means for holding the greater portion of said flange out of contact with said car side to form a vertically open air space, and securing means for said flange engaging said spacing means.

In testimony whereof I affix my signature in presence of two witnesses.

DAVID W. HAWKSWORTH.
